(57) **CLAIM**

The ornamental design for a demonstration tool, as shown and described.

DESCRIPTION

The patent or application file contains at least one drawing executed in color. Copies of this patent or patent application publication with color drawing(s) will be provided by the Office upon request and payment of the necessary fee.
FIG. 1 is a perspective view of a demonstration tool showing my new design;

FIG. 2 is a front view of the demonstration tool of FIG. 1;
FIG. 3 is a rear view of the demonstration tool of FIG. 1;
FIG. 4 is a left-side view of the demonstration tool of FIG. 1;

FIG. 5 is a right-side view of the demonstration tool of FIG. 1;

FIG. 6 is a top plan view of the demonstration tool of FIG. 1; and,

FIG. 7 is another perspective view of the demonstration tool of FIG. 1.

1 Claim, 7 Drawing Sheets
(7 of 7 Drawing Sheet(s) Filed in Color)
